UNITED STATES PATENT OFFICE.

ROY B. FEHR, OF CLEVELAND, OHIO, ASSIGNOR TO RAIL WELDING & BONDING COMPANY, OF CLEVELAND, OHIO, A CORPORATION OF DELAWARE.

RAIL JOINT.

Application filed January 28, 1925. Serial No. 5,207.

To all whom it may concern:

Be it known that I, Roy B. FEHR, a citizen of the United States, residing at Cleveland, in the county of Cuyahoga and State of 5 Ohio, have invented certain new and useful Improvements in Rail Joints, of which the following is a specification.

My invention is an improvement in rail joints and more particularly relates to the 10 type of joint formed by welding.

Rail joints as heretofore used, have failed to endure to a practical degree the excessive loads imposed upon them, and this is more apparent where the loads are attended 15 by high speed, such as a fast moving car or train. I have found that attempts to strengthen welded rail joints succeeded so well that the joint in some respects became stronger than the rail, the latter often being 20 somewhat weakened by the nature and formation of the joint. Bending stresses concentrated in the rails at the ends of the fish plates coupled with stresses due to base seam 25 welds extending to the ends of the plates are believed to have been the cause of a majority of rail breakages at those points.

It is therefore an important object of my invention to overcome the defects above stated and to construct a strong rail joint 30 in which the strength of the various parts will be more or less evenly balanced against each other and that of the rails.

It is also an object of my invention to prevent the concentration of load stresses at 35 any one point, particularly in the rails at the ends of the fish plates.

It is a further object of my invention to distribute more evenly the stresses in a rail joint during the passing of a wheel load 40 thereover.

A further object of my invention is to provide a welded rail joint which is designed to reduce, if not entirely eliminate, rail 45 breakages at the ends of the welded fish plates.

Other objects and advantages will become apparent during the progress of the description of an embodiment of my invention, reference being had to the accompanying drawings 50 in which like numerals are used to designate like parts throughout.

In the drawings:

Fig. 1 is a side elevation of the rail joint showing the preferred form;

Fig. 2 is a section showing the invention 55 applied to rails of the girder type;

Fig. 3 is a section showing the invention applied to rails of the T-head type;

Fig. 4 is a side elevation of a second form 60 of my invention in which fish plates of equal lengths are disposed in staggered relation to each other; and

Fig. 5 is a side elevation of a third form 65 of my invention in which the base seam welds are interrupted at the gap.

Referring to the drawings, I have shown the abutting ends of each of two aligned rails in which 1 represents the webs, 2 the heads and 3 represents the base flanges. Fish plates 4 and 4' are provided with the 70 usual bolt holes which register with the usual openings in the rail ends. These bolt holes may be slightly offset for drifting. Bolts 6 are placed through the plates and rails and are secured in place by nuts. 75

It is to be understood that my invention may be applied to different types of rails such as the girder type shown in Fig. 2 or the T-head type shown in Figs. 1 and 3.

In Fig. 1 I have shown fish plates 4 and 80 4' of different lengths one of which is adapted to be secured to one side of the rail ends and the other to the opposite side of the rail ends.

It is an important object of my invention 85 to overcome the tendency of a passing wheel load to concentrate the stresses imparted to the rail joint at one point. I, therefore, provide in the preferred embodiment of my invention, fish plates of different lengths 90 secured to the rail ends so that the ends of one of the plates will extend equally beyond the corresponding ends of the other plate.

The fish plates 4 and 4' are preferably 95 provided along their upper edges with outwardly projecting flanges 7 and 7', respectively, and along their lower edges with correspondingly outwardly projecting flanges 8 and 8'. These flanges abut the 100 under surfaces of the rail heads and the upper surfaces of the rail bases, respectively.

Along the upper flanges at a point where the rail material contacts with the flanges, 105 I provide longitudinal weld metal receiving surfaces 9 and 9', respectively extending well beneath the adjacent rail head to form

a groove and extending forwardly of said rail head to form a ledge, for securing weld metal, as shown at 11 in Fig. 3. The lower flanges 8 and 8' are secured to the base flanges 3 of the rail by welding as at 12 and 12' in Fig. 3.

In this connection, it is important that the weld metal receiving surface extend to a point at or near the end of the fish plate, 10 so that the upper weld can extend along the full length of the plates, if strength demands full length welds; but the lower weld should extend only to points which are several inches within the ends of the 15 plates so that the natural concentration of stresses which occur at a change of section will not be augmented by welding stresses.

The ends of each or of one of the fish plates may be slotted longitudinally as at 20 14 and 14'. In some cases these slots need only run to the first bolt hole on each end of the plates, but with excessive stresses or when using rails of greater or less weight, it may be advisable to continue the slots, to a 25 point beyond the bolt hole and to terminate said slots in an opening (not shown). In either instance the hole or opening communicating with the slot will prevent the plate from cracking at the slot.

30 The slots in the fish plates give a certain amount of shock absorbing qualities to the entire joint and particularly at a point just ahead and just beyond the abutting edges of the rails, that is, near the ends of the fish plates. Furthermore, there will be a more 35 gradual change in cross section (and section modulus) from the rail and the joint, and consequently there is a batter distribution 40 of stresses than there is in present forms of joints, when a rolling load (wheel load) is applied.

45 Thus it will be noted that in the proposed type of rail joint the very desirable "fillet" effect for obtaining the more even distribution of stresses when the joint is called upon to act as a beam under wheel loads, is obtained by one or a combination of the following methods:—First, by providing staggered seams to distribute welding stresses; 50 second, staggering the plates to insure complete or partial staggering of the seams, and to give more gradual change in cross section (section modulus); third, by slotting the ends of fish plates to give more gradual 55 change in section modulus; and fourth, by stopping the base seam welds several inches short of the plate ends, so that welding stresses will not augment stresses in rails at ends of plates due to bending.

60 In a modified form of my invention as shown in Fig. 4, I have provided fish plates 25 and 26 of equal length secured to each side of the abutting rail ends in staggered relation. In this form of my invention I have provided a different means for secur-

ing the results accomplished by the form shown in Figs. 1, 2 and 3.

Referring to Fig. 4, fish plates 25 and 26 are in staggered relation and are each provided with top welds 27 extending nearly to 70 the ends of the plates, while the base welds 28 stop several inches from the ends of the plates.

In Fig. 5 I have shown another form of 75 my invention which is similar to the form shown in Fig. 4 in that the fish plates 31 and 32 are of the same length and are secured to the rail ends in staggered relation and may be slotted. In the present form, however, it will be noted that the base weld 80 33 is interrupted at 34 for a short distance on each side of the plate directly opposite the point of contact of the rail ends. The plates may be slotted as at 35 and 36 as in the preferred form shown in Fig. 1. 85

It is to be understood that various changes may be made in the construction as described without departing from the spirit of my invention or the scope of the subjoined claims. 90

I claim:—

1. The method of constructing a seam welded rail joint which comprises aligning adjacent rail ends, fitting joint plates in fishing relation on opposite sides of the rail 95 ends and integrally uniting said plates to said rail ends by head and base seams, the base seams being relatively short with respect to the length of the plates and the length of the head seams and being located 100 in their entirety remote from the ends of the plates and being substantially centrally located with respect to said plates.

2. The method of constructing a seam welded rail joint which comprises aligning 105 adjacent rail ends, fitting joint plates in fishing relation on opposite sides of the rail ends, each said plate having slots extending longitudinally from the opposite ends thereof, and integrally uniting said plates to said rail ends by head and base seams, the base seams being relatively short with respect to the length of the plates and the length of the head seams and being located 110 in their entirety remote from the ends of the plates and being substantially centrally located with respect to said plates.

3. The method of constructing a seam welded rail joint which comprises aligning adjacent rail ends, fitting in fishing relation on opposite sides of the rail ends joint plates of channel shaped cross section having their ends unaligned, said plates each having a top flange provided with a weld metal receiving surface at the top edge extending well beneath an adjacent rail head to form a recess and extending forwardly of the said rail head to form a ledge and having a base flange extending outwardly toward the edge of the rail base but stop- 115 120 125 130

ping short thereof and having an upright seam weld metal engaging surface, and an outwardly bowed web portion between said flanges, each said plate having holes through 5 the web portion thereof, said holes being slightly unaligned with respect to corresponding holes in the rail ends, and fusing adjacent portions of the rail head, the upper surface of each plate and additional 10 metal to form a seam weld disposed in each recess and on each ledge and integrally united to the rail head and plate, said head seams stopping short of the ends of the plates, and forming seam welds integrally 15 uniting the plates and rail bases, said base seams being relatively short with respect to the length of the plates and the head seams, being approximately equidistant from the ends of the plates, and all of said 20 seams ending in different vertical planes.

4. The method of constructing a seam welded rail joint which comprises aligning adjacent rail ends, fitting fishing relation on opposite sides of the rail ends joint plates 25 of channel shaped cross section having their ends unaligned, said plates each having a top flange provided with a weld metal receiving surface at the top edge extending well beneath the adjacent rail head to form 30 a recess and extending forwardly of the said head to form a ledge and having a base flange extending outwardly toward the edge of the rail base but stopping short thereof and having an upright seam weld 35 metal engaging surface, and an outwardly bowed web portion between said flanges, each said web portion having narrow slots extending longitudinally from the opposite ends thereof, each said plate having holes 40 through the web portion thereof, said holes being slightly unaligned with respect to corresponding holes in the rail ends, and fusing adjacent portions of the rail head, the upper surface of each plate and additional weld 45 metal to form a seam weld disposed in each recess and on each ledge and integrally united to the rail head and plate, said head seams stopping short of the ends of the plates, and forming seam welds integrally 50 uniting the plates and rail bases, said base seams being relatively short with respect to the length of the plates and the head seams, being approximately equidistant from the ends of the plates, and all of said 55 seams ending in different vertical planes.

5. A seam welded rail joint comprising aligned adjacent rail ends, joint plates arranged on opposite sides of the rail ends engaging the heads and bases of the rails in fishing relation, said plates being united to the rails along their top and bottom edges by means of seam welds, the base seams being relatively short in total length with respect to the length of the plates and total 60 length of the head seams, and being located 65

in their entirety remote from the ends of the plates and being substantially centrally located with respect to said plates.

6. A seam welded rail joint comprising aligned adjacent rail ends, channel shaped 70 joint plates arranged on opposite sides of the rail ends engaging the heads and bases of the rails in fishing relation, each said plate having a surface along the top edge thereof extending well beneath the adjacent rail head to form a recess and forwardly of said head to form a ledge, seam weld metal in each said recess and on each said ledge integrally united to the rail heads 75 and plates, and base seam welds integrally 80 uniting the plates and rail bases, said base seam welds being relatively short in total length with respect to the length of the plates and total length of the head seams, and the ends of said base seams being approximately equidistant from the ends of 85 the plates.

7. A seam welded rail joint comprising aligned adjacent rail ends, channel shaped 90 joint plates arranged on opposite sides of the rail ends engaging the heads and bases of the rails in fishing relation and having their ends unaligned, each said plate having a surface along the top edge thereof extending well beneath the adjacent rail head to form a recess and forwardly of the said head to form a ledge, seam weld metal in each said recess and on each said ledge integrally 95 united to the said plates and rail heads, said seam welds stopping short of the ends of the plates, and base seam welds integrally 100 uniting the rail bases and the plates, said base seam welds in total length being relatively short with respect to the length of the plates and total length of the head seams, the ends of said base seams being approximately equidistant from the ends of the plates and all of said seams terminating in different vertical planes.

8. A seam welded rail joint comprising 110 aligned adjacent rail ends, joint plates arranged on opposite sides of the rail ends engaging the heads and bases of the rails in fishing relation and having web portions slotted longitudinally from the ends thereof, one of said plates being longer than the other and extending approximately an equal distance beyond the ends of the short plate and said plates being united to the rails 115 by means of head and base seam welds.

9. A seam welded rail joint comprising aligned adjacent rail ends, channel shaped 120 joint plates arranged on opposite sides of the rail ends engaging the head and base of the rails in fishing relation, said plates having web portions between the rail heads and bases provided with longitudinally extending slots, each said plate having a surface along the top edge thereof extending well 125 beneath the adjacent rail head to form a 130

recess and forwardly of said head to form a ledge, seam weld metal in each said recess and on each said ledge integrally united to the said plates and heads, and base seam welds integrally uniting the rail bases and the plates, said base seam welds being relatively short in total length with respect to the plates and the ends of said seam welds being approximately equidistant from the ends of the plates.

10. A seam welded rail joint comprising aligned adjacent rail ends, channel shaped joint plates arranged on opposite sides of the rail ends engaging the heads and bases of the rails in fishing relation and having their ends unaligned, said plates having web portions between the rail heads and bases provided with longitudinally extending slots, each said plate having a surface along the top edge thereof extending well beneath the adjacent rail head to form a recess and forwardly of said head to form a ledge, seam weld metal in each said recess and on each said ledge integrally united to the said plates and heads, and base seam welds integrally uniting the rail bases and the plates, said base seam welds being relatively short in total length with respect to the plates and the ends of said seam welds being approximately equidistant from the ends of the plates.

11. A seam welded rail joint comprising aligned adjacent rail ends, joint plates arranged on opposite sides of the rail ends engaging the heads and bases of the rails in fishing relation, each said plate having a web portion, said plates being united to the rails along their top and bottom edges by means of seam welds, and provided with longitudinally extending narrow slots terminating in holes through the plates.

12. A seam welded rail joint comprising aligned adjacent rail ends, joint plates arranged on opposite sides of the rail ends engaging the heads and bases of the rails in fishing relation, each said plate having a web portion, said plates being united to the rails along their top and bottom edges by means of seam welds, and provided with longitudinally extending narrow slots at opposite ends thereof said slots terminating in holes through the plates.

13. A seam welded rail joint comprising aligned adjacent rail ends, channel shaped joint plates arranged on opposite sides of the rail ends engaging the heads and bases of the rails in fishing relation and having a web portion therebetween provided with slots extending from the ends thereof inwardly in a longitudinal direction, said slots terminating in holes through the plates, each said plate having a surface along the top edge thereof extending well beneath the adjacent rail head to form a recess and forwardly of the said head to form a ledge,

seam weld metal in each said recess and on each said ledge integrally united to the said plates and the rail heads, said seam welds stopping short of the ends of the plates and base seam welds integrally uniting the rail bases and the plates, said base seam welds being relatively short in total length with respect to the length of the plates, the ends of said base seams being approximately equidistant from the ends of the plates and all of said seams terminating in different vertical planes.

14. A seam welded rail joint comprising aligned adjacent rail ends, channel shaped joint plates arranged on opposite sides of the rail ends engaging the heads and bases of the rails in fishing relation, one of said plates being longer than the other and extending approximately an equal distance beyond each end of the shorter plate, the web portions of each plate being slotted longitudinally from the ends thereof and each said plate having a surface along the top edge thereof extending well beneath the adjacent rail head to form a recess and extending forwardly of the said head to form a ledge, seam weld metal in each said recess and on each said ledge integrally united to the said plates and the rail heads, seam welds integrally uniting the rail bases and the plates, said base seam welds being relatively short in total length with respect to the length of the plates; the ends of said base seam welds being approximately equidistant from the ends of the plates and all of said seams terminating in different vertical planes.

15. A joint plate for a welded rail joint having surfaces adapted to engage the under surface of a rail head and the upper surface of a rail base and a web portion therebetween, said web portion being provided with longitudinally narrow extending slots which terminate in holes through the plate.

16. A joint plate for a welded rail joint having head and base flanges adapted to cooperate with the underside of a rail head and the upper side of a rail base respectively, and having a web portion between said flange portions provided with longitudinally extending slots which terminate in holes through the plate.

17. A joint plate for a welded rail joint having head and base flanges adapted to cooperate with the underside of a rail head and the upper side of a rail base respectively, and having an outwardly bowed web portion between said flange portions provided with longitudinally extending narrow slots.

18. A joint plate for a welded rail joint, having head and base flanges adapted to cooperate with the underside of a rail head and the upper side of a rail base respectively, and having a web portion between said

flange portions, said head flange having a top surface adapted to form a recess extending well beneath a rail head and to extend forwardly from the rail head to form a ledge, said base flange having a substantially vertical seam weld engaging surface, and said web portion being provided with longitudinally extending slots.

19. A joint plate for a welded rail joint having head and base flanges adapted to cooperate with the underside of a rail head and the upper side of a rail base respectively, and having an outwardly bowed web

portion between said flange portions, said head flange having a top surface adapted to form a recess extending well beneath a rail head and to extend forwardly from the rail head to form a ledge, said base flange having a vertical seam weld engaging surface, and said web portions being provided with longitudinally extending slots. 15

In testimony whereof I hereunto affix my signature this 18 day of July, 1925.

ROY B. FEHR.
